UNITED STATES PATENT OFFICE.

NORMAN SAMUEL MAHAFFY, OF TORONTO, ONTARIO, CANADA, ASSIGNOR TO HOULDING AND COLEMAN LIMITED, OF TORONTO, CANADA.

MEANS FOR KNITTING NECKTIES.

Application filed September 27, 1926. Serial No. 138,085.

The principal objects of the invention are, to produce in a tubular knitted tie a section with a smooth close knit stitch extending around a portion of the circumference of a 5 tubular fabric, and to provide in a tie formed with a fancy stitch a smooth inner side to the neck band portion to enable it to be slipped freely around the neck.

A further object is to provide a simple 10 form of mechanism which may be readily attached to a standard knitting machine to accomplish the desired result.

The principal feature of the invention consists in providing means for manipulating 15 the needles in such a manner as to knit a tuck stitch for half a revolution of the member rotating about the needle cylinder and a plain stitch for the other half.

In the accompanying drawings, Figure 1 20 is a plan view of a "Brinton" type of knitting machine.

Figure 2 is a side elevation of a portion of a machine looking in the direction of arrow, Figure 1 and illustrating the arrangement 25 of the attachments involved in the present invention.

Figure 3 is a detail elevational view showing the special mechanism arranged each side of the needle cylinder for shifting the 30 needles from a tuck stitch to a plain stitch each half revolution.

In the "Brinton" type of knitting machine the stationary needle cylinder 1 is surrounded by a rotating carriage 2 which carries the pattern wheels 3 and the tucking members 4 for manipulating the needles in the cylinder to form tucked or plain stitches. This construction is a well known mechanism and is illustrated in United States 40 Patent 977,852 of December 6, 1910 and United States Patent 953,122 of March 29, 1910.

Each tucking member 4 is formed with a triangular bevelled end 5 and said member tilts on a pivot in the bracket 6.

The tucking bar plunger 7, which is not a part of this present invention but is part of the usual mechanism, is operated from the cam drum 8 in the ordinary manner to engage the bevelled end of the tucking bars as they are carried past the plunger in the rotation of the carriage.

The present invention consists in applying to the standard knitting machine as above

mentioned special devices for operating the 55 tucking bars at certain periods different from the ordinary mechanism and a plunger mechanism 9 is arranged at one side of the rotatable carriage, substantially in a position in right angular relation to the plunger 60 7 and diametrically opposed to the plunger 9 is a rocker bar 10 pivotally mounted in a bracket 11.

The plunger 9 here shown is operated by a plate 12 which operates on a pivot in the 65 supporting bracket 13 and this plate is oscillated by a rod 14 which is pivotally mounted in a bracket 15 secured to the frame of the machine and has an extension 16 extending downwardly and resting upon the 70 cam drum 17.

The drum 17 which operates intermittently is provided with a plurality of cam projections 18 which as the drum rotates lift the extension end 16 and operate the 75 rod 14 to tilt the plunger plate on its pivot to operate the plunger 9 to move it into or out of the path of the tucking bars 4.

The operation of the tucker bar 4 causes a shift in the stitch produced and as the 80 frame rotates about the needle cylinder a half circle is completed with a pattern or tuck stitch. The rocker bar 10 which is mounted diametrically opposite to the plunger 9 then operates to shift the position 85 of the tucker 4 and change the stitch to a plain stitch for the other half circle.

The rocker bar 10 is operated in a very simple manner by a rod 19 which is pivotally mounted intermediate of its length on 90 a bracket 20 and the down-turned end 21 engages the surface of a cam 22 which is provided with a semi-circular portion 23 of a larger diameter than the remaining portion.

The manipulation of the apparatus is very simple. The cam 22 and cam drum 17 operate with such relative movements as to ensure the operation of the plunger 9 and rocker member 10 in proper concert so that 100 the tucking members 4 carried on the rotatable carriage will operate at such periods that they will manipulate the needles so as to knit a fancy or tuck stitch for half a revolution in each row and then knit a plain 105 stitch for the remaining half of the row.

The relative location of the plunger 9 and the rocker member 10 may be altered to vary

the relative portion of the circumference to be occupied either by the plain stitch or by the fancy stitch.

When a tie is being knitted with the neck band portion formed with a plain back in the manner described, the ordinary tucker bar plunger 7 is of course not operated but its place is taken by the plunger 9 and the rocker 10 which shift the stitch half way around independent of the tucker bar plunger 7. The result of this manipulation of the needles is that the machine produces a neck-tie knitted in tubular form with the inside of the band portion knitted in a short smooth stitch with the outside portion knitted in a fancy stitch, while the body of the tie is knitted completely around with a fancy stitch by bringing into action the tucker bar plunger at the desired points in the length of the tie as the knitting proceeds.

The attachment does not interfere in any manner with any of the operating parts of the knitting machine and it is very simple to apply and costs very little to install.

25 What I claim as my invention is:—

1. In means for knitting neckties, the combination with a tubular knitting machine having tucker bars arranged on the rotating carriage and the usual means operatively arranged at one side of the carriage for manipulating said tucker bars, of means operatively arranged at one side of said carriage adapted to manipulate the tucker bars at a predetermined point in advance of said usual manipulating means, means operatively arranged and adapted to manipulate the tucker bars at a point substantially equidistant beyond said usual manipulating means, and means for actuating the advanced and delayed manipulating means when said usual manipulating means is at rest.

2. In a tubular knitting machine the combination with the rotatable carriage having a pair of diametrically opposed tucker bars arranged thereon and the usual tucker bar manipulating means, of separate means arranged in diametrically opposite relation spaced equally either side of said usual tucker bar manipulating means and adapted to operate said tucker bars when the usual manipulating means is at rest in advance of and beyond its point of operation to prevent the tucking of the stitches in each course from a point in advance of the usual manipulating means to a point therebeyond.

3. In means for knitting neckties, the combination with a tubular knitting machine

having tucker bars arranged on the rotating carriage, and the usual means operatively arranged at one side of the carriage for manipulating said tucker bars of a tucker bar plunger arranged at one side of the rotating head of the machine adapted to engage and tilt the tucker bars in advance of said usual manipulating means, means for intermittently operating said plunger, means operatively arranged at the opposite side of the head adapted to engage and reset the tucker bar at a point beyond said usual manipulating means when the latter is at rest, and means for periodically operating said resetting member.

4. In a tubular knitting machine, the combination with the needle cylinder, having a rotatable carriage and tucker bars radially mounted on said carriage co-operating with the needles of the cylinder, and the usual means operatively arranged at one side of the carriage adapted to engage and manipulate said tucker bars of a tucker bar plunger arranged at one side of the head adapted to cooperate with said tucker bars in advance of said manipulating means, a rocker member operatively engaging with said plunger, rotatable cam members adapted to operate said rocker members intermittently, and intermittently operating means arranged at the opposite side of the carriage from said tucker bar plunger adapted to engage the tucker bars after said bars pass the usual manipulating means when the latter is at rest to effect the changing of the stitch therebeyond for a portion of the circumference of the cylinder.

5. In a tubular knitting machine, the combination with the needle cylinder, a rotatable carriage, tucker bars radially mounted on said carriage co-operating with the needles of the cylinder, and the usual means operatively arranged at one side of said carriage adapted to engage and manipulate said tucker bars of a tucker bar plunger arranged at one side of said head, in advance of said usual manipulating means, means for intermittently operating said tucker bar plunger, a pivotal rocker member arranged at the opposite side of the head from said plunger and beyond said usual manipulating means and adapted to engage the tucker members, when the usual manipulating means is at rest, a pivotal rod connected with said rocker member, and a cam adapted to operate said pivotal rod and said rocker member for a half revolution of the cylinder.

NORMAN SAMUEL MAHAFFY.
